United States Patent Office

Des. 194,132
Patented Nov. 20, 1962

194,132

BOTTLE

Roy Countryman, Jackson, Miss., assignor to
B. F. Trappey's Sons Inc., New Iberia, La.

Filed Apr. 26, 1961, Ser. No. 64,916

Term of patent 14 years

(Cl. D58—6)

FIG. 1.

FIG. 2.

FIG. 3.

The rear and side not shown are substantially the same as the front and side shown.

I claim:

The ornamental design for a bottle, as shown and described.
